UNITED STATES PATENT OFFICE.

LOUIS G. LAUREAU, OF PHILADELPHIA, PENNSYLVANIA, ASSIGNOR TO
GORDON, STROBEL & LAUREAU, OF SAME PLACE.

CONVERTER.

SPECIFICATION forming part of Letters Patent No. 358,559, dated March 1, 1887.

Application filed July 24, 1886. Serial No. 208,943. (No model.)

To all whom it may concern:

Be it known that I, LOUIS G. LAUREAU, of Philadelphia, Philadelphia county, Pennsylvania, have invented certain new and useful 5 Improvements in Converters, of which the following is a specification.

This invention pertains to converters for use in the treatment of molten metal by the Bessemer or pneumatic processes. 10 The improvements will be readily understood from the following description, taken in connection with the accompanying drawings, in which—

Figure 1 is a front elevation, half vertical section, of a converter embodying my improvements; Fig. 2, a horizontal section of the same at the tuyere-level, and Fig. 3, a horizontal section of a portion of the same at the same level. 15

The figures of the drawings are upon different scales.

In the drawings, A indicates the upper portion of the converter; B, the trunnions; C in Fig. 2, a dotted line representing the vertical plane of the axis of the trunnion; D, the tuyeres, arranged in oppositely-disposed groups below each trunnion, thus leaving two sides of the converter free from tuyeres; E, a wind-conduit arranged to lead the blast to the tuyeres; F, a conduit connecting the conduit E with the trunnion, through which the blast is received; G, the bottom of the converter, the same being separable from the parts above; H, that portion of the converter containing the tuyeres and lying between the bottom G and the top A, and hereinafter designated as the "tuyere-zone;" J, bolts securing the bottom of the converter and the top and the tuyere-zone together, these bolts engaging circumferential flanges on the converter-top, and on the bottom, and thus serving to clamp the tuyere-zone between the bottom and the top of the converter; K, the line of juncture between the converter-top and the tuyere-zone, and L the line of juncture between the tuyere-zone and the converter-bottom. 20 25 30 35 40 45

The linings of the converter-top, the tuyere-zone, and the bottom may be formed of shaped brick or of rammed ganister. The grouping of the tuyeres below the trunnions, thus leaving the sides of the converter free of tuyeres, permits of the tuyeres becoming uncovered by the molten metal at a tipping angle very much

slighter than if the tuyeres were distributed entirely around the converter, thus permitting the pouring to take place at a much less angle of tipping than usual. The top of the converter and the tuyere-zone and the bottom are separately lined, and these parts are then secured by the bolts J, the lines of juncture being probably luted. When so arranged, there is but little wearing away of the lining of the bottom. In fact, when everything is working well, the bottom gets thicker instead of thinner, and the top wears but little, the bulk of the wear coming upon the tuyere-zone. When the tuyere-zone is too much worn for further use, it may be repaired, or be replaced by a duplicate, by simply disconnecting the bolts J, which allows the parts to separate, so that the tuyere-zone can be removed, &c. 55 60 65 70 75

The conduit may completely encircle the converter, or it may be only so far as may be needed to make proper connection with the tuyeres. 80

The bolts J may, if desired, be passed directly through the wind-conduit through tubes formed in the wind-conduit, as shown in Fig. 3.

It is common practice to make the lower portion of a converter in the form of a removable section containing either horizontal, vertical, or inclined tuyeres, the lining of the tuyere-zone being integral with the lining of the bottom or floor of the converter. In such arrangement the lining of the tuyere-zone could not be restored without affecting the lining of the bottom or floor of the converter, and is thus broadly distinguishable from my improved construction, in which the lining of the tuyere-zone is restorable without disturbance of the lining of the bottom or floor. 85 90 95

I claim as my invention—

In a converter, a converter-top having a lining, a converter-bottom having a lining, a lined tuyere-zone disposed between the converter-top and the converter-bottom and separable therefrom, and means for clamping the tuyere-zone between the converter-top and the converter-bottom, combined substantially as and for the purpose set forth. 100

LOUIS G. LAUREAU.
